Primary Examiner — Jonathan J Han

Assistant Examiner — Caitlin Mackenzie Williams

(57) CLAIM

The ornamental design for pants, as shown and described.

DESCRIPTION

FIG. 1 is a top-rear perspective view of pants;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

The dot-dash broken lines define the bounds of the claimed design and form no part thereof. The broken lines depicting the remainder of the article form no part of the claimed design.

1 Claim, 7 Drawing Sheets(56)
